UNITED STATES PATENT OFFICE.

HENRY A. FRAMBACH, OF KAUKAUNA, WISCONSIN.

MACHINE FOR APPLYING GUM OR GLUE TO SURFACES OF WEBS OF PAPER.

SPECIFICATION forming part of Letters Patent No. 596,966, dated January 4, 1898.

Application filed April 16, 1897. Serial No. 632,365. (No model.)

To all whom it may concern:

Be it known that I, HENRY A. FRAMBACH, a citizen of the United States, and a resident of Kaukauna, in the county of Outagamie and State of Wisconsin, have invented an Improved Machine for Applying Gum or Glue to the Surface of a Web of Paper, of which the following is a specification.

This invention relates to machinery for applying gum or glue to the surface of a web of paper, and relates particularly to machinery for so applying gum or glue to a web of paper which is designed and intended to be cut into tie-bands for use in laundries for securing shirts in folded position.

Heretofore the general practice has been to apply gum or glue to tie-bands by hand after the web of paper has been cut or severed into bands, it having been found practically impossible to apply gum or glue thereto by machinery while united in a web, owing principally to the difficulty of distributing such gum or glue evenly upon the surface of said web, a thick strip of gum or glue forming across the web where the gumming or gluing device leaves said web. Owing also to the consistency of said gum or glue, it stretches out in the form of strings, which are apt to adhere to the surface of the paper outside of the portions thereof which it is desired to gum or glue in an undesirable and objectionable manner.

The object of my invention is to provide improved means to apply gum or glue evenly to desired portions of the surface of a web of paper of limited areas, which said gummed or glued portions of said web of paper shall be separated from each other by unglued spaces of uniform length.

A machine embodying my invention consists of the various features, combinations of features, and details of construction herein-after described and then pointed out in the claims.

In the accompanying drawings a machine embodying my invention is fully illustrated.

Figure 1 is a side elevation of a machine embodying my invention. Fig. 2 is a vertical longitudinal sectional view thereof. Fig. 3 is a transverse sectional view thereof, on the line 3-3 of Fig. 2, looking in the direction indicated by the arrows; and Fig. 4 is a plan view of a

web of paper to which gum or glue has been applied by means of my improved machine, the gummed areas being indicated by the shaded portions thereof and the method of severing the same to form individual bands being indicated by dotted lines.

As shown in the drawings, the operative parts of my improved machine are supported in a frame which consists of lateral frame-sections A, secured together by transverse frame members A'.

Revolutionly mounted in suitable bearings formed in the lateral sections A of the machine-frame is a roll B, the underside of which runs in a gum or glue fountain B', the bottom b of which is hollow, and the interior of said hollow bottom being connected with a suitable source of steam-supply by a pipe b', through which steam is admitted thereto. The steam so admitted to the hollow bottom b of said gum or glue fountain will operate to maintain the gum or glue therein in a liquid state and likewise affords convenient means for regulating the consistency thereof.

Secured to a shaft b², revolutionally mounted in suitable bearings in the machine-frame above the roll B, is a segment of a cylinder B², the circumferential dimension of which is equal to the desired width of the gummed or glued areas on the web of paper.

The shaft b² is so located relatively to the roll B that as said shaft rotates the perimeter of the cylindrical segment B² will come into contact with the perimeter of said roll B.

Positive rotary movement in the directions indicated by the arrows is imparted to said roll B and to the shaft b² by suitable means.

As shown, the roll B is driven from any suitable source of power (not shown) by means of a belt applied to a driving-pulley B³, rigidly secured to the shaft of said roll, and the shaft b² is driven from the shaft of the roll B by means of spur-gears b³ b⁴, secured to the shaft of the roll B and to the shaft b², respectively, the sizes of said gears being such that the segmental cylinder B² will be driven at the same surface speed as the roll B. Preferably, also, the roll B is driven through the medium of a clutch, which affords convenient means for starting and stopping the same.

Revolutionally mounted in suitable bearings

formed in the machine-frame is a roll B⁴, the position of which is such that as the shaft b² rotates the perimeter of the segmental cylinder B² will come into contact with the perimeter of said roll B⁴.

Positive rotary movement in the direction indicated by the arrow is imparted to the roll B⁴ by means of a spur-gear b⁵, secured to the shaft thereof, which meshes with the gear b⁴ on the shaft b², the size thereof being such that said roll B⁴ will be driven at the same surface speed as said segmental cylinder B².

Supported above the segmental cylinder B² in such manner as to be bodily movable toward and from the same is a scraper or doctor B⁵. As shown, said scraper or doctor is provided with sleeves b⁶ at its opposite ends, which are fitted to studs b⁷, rigidly secured in the machine-frame. Threaded to the studs b⁷ are nuts b⁸, between which and the tops of the sleeves b⁶ are inserted coiled springs b⁹, which operate in an obvious manner to hold the scraper or doctor B⁵ normally yieldingly advanced, in which position the lower edge of said scraper or doctor extends below the surface of said segmental cylinder B². My improved machine also comprises means to raise said scraper or doctor intermittently to allow said segmental cylinder to pass under it and to release said scraper or doctor just before said segmental cylinder passes from beneath it, allowing said scraper or doctor to descend into contact with the surface of said segmental cylinder at a point adjacent to its rear edge, thus severing any strings of gum or glue which may have formed between said segmental cylinder and the roll B and scraping any superfluous gum or glue from the rear edge of said segmental cylinder. As shown, said means are as follows:

Secured to the shaft b² adjacent to its opposite ends are similar cams B⁶, upon which the scraper or doctor B⁵ is normally supported. Said cams B⁶ are of such size and shape and are secured to the shaft b² in such position that as said shaft b² rotates they will raise said scraper or doctor above and out of the path of travel of the segmental cylinder B², allowing said segmental cylinder to pass freely beneath the same. Said cams are also cut away, substantially as shown at b¹⁰, in such manner that said scraper or doctor B⁵ will be suddenly released just before said segmental cylinder B² passes from beneath it, thus allowing said scraper or doctor to descend under the influence of the springs b⁹ into contact with the surface of said segmental cylinder adjacent to its rear edge in the desired manner.

The lower edge of the scraper or doctor is preferably beveled on its front side, leaving a blunt chisel edge about one-eighth of an inch thick. I find in practice that a scraper or doctor of this shape is best adapted to perform the desired function thereof.

The gum or glue is applied to the web of paper by the segmental cylinder B², which will be of such size that the periphery of the

complete cylinder will be equal to the desired distance between successive gummed or glued areas.

A machine embodying my invention also comprises a drying-cylinder C. As shown, said cylinder C is hollow, and steam is admitted to the interior thereof through one of its supporting-trunnions c, which is made hollow and is connected with a source of steam-supply in substantially the same manner that steam is admitted to the drier-rolls of a paper-making machine, which will be clearly understood by persons familiar with such machinery without a detailed description thereof. Rotary movement in the direction indicated by the arrow is imparted to the drier C by means of a chain-belt C', applied to sprocket-wheels C² C³, secured to the shaft of the roll B and to one of the trunnions of the drier-cylinder C, respectively, the relative sizes of said sprocket-wheels being such that the surface speed of said drying-cylinder C will be the same as that of the other positively-driven drums and rolls over which the web of paper passes.

Paper to feed the machine is supplied thereto from a roll D, supported in suitable bracket-bearings formed on the machine-frame. Said roll is preferably provided with a suitable friction-brake to retard its rotation and maintain the web of paper taut as it is drawn therefrom in a familiar manner.

In the drawings, D' designates the web of paper in which the machine is operating.

Fig. 4 of the drawings represents a portion of a web of paper after passing through my improved machine, the darkened or shaded portions d indicating those parts to which the gum or glue has been applied. Separate bands gummed or glued at one end only are formed by slitting the web D' on longitudinal lines d' and severing it on transverse lines d².

The operation of my improved gumming or gluing machine is as follows: The web of paper D' is delivered from the roll of paper D around guide-rolls d³ into contact with the surface of the roll B⁴, so that the segmental cylinder B² will come into contact therewith as the shaft b² rotates. From the roll B⁴ the web D' passes around the drying-cylinder C, whence it is conducted over guide-rollers d⁴ to a suitable reel. (Not shown.)

I claim—

1. In a mechanism for applying gum or glue to the surface of a web of paper, the combination of a gum or glue fount, a gumming or gluing roll running therein, a revolute supporting-roll, a segmental cylinder revolubly mounted in such position that, as it rotates, the perimeter thereof will come into contact with the perimeters of said gumming or gluing roll and said supporting-roll, means to impart rotary movement to said gumming or gluing roll, to said supporting-roll and to said segmental cylinder, a scraping-knife reciprocally supported adjacent to said segmental cylinder, means to maintain said scraping-

knife, normally, advanced, means to remove said scraping-knife from the path of the segmental cylinder and means to release said scraping-knife just before said segmental cylinder passes from beneath it, substantially as described.

2. In a mechanism for applying gum or glue to the surface of a web of paper, the combination of a gum or glue fount, a gumming or gluing roll running therein, a revolute supporting-roll, a segmental cylinder revolutely mounted in such position that, as it rotates, the perimeter thereof will come into contact with the perimeters of said gumming or gluing roll and said supporting-roll, means to impart rotary movement to said gumming or gluing roll, to said supporting-roll and to said segmental cylinder, a scraping-knife reciprocally supported adjacent to said segmental cylinder, springs applied to said scraping-knife and adapted to maintain the same, normally, advanced or depressed, cams secured to the shaft of said segmental cylinder and adapted to raise said scraping-knife to allow said segmental cylinder to pass it and to release said scraping-knife just before said segmental cylinder passes from beneath it and a driven drying-cylinder, substantially as described.

3. In a mechanism for applying gum or glue

to the surface of a web of paper, the combination of a gum or glue fount having a hollow bottom to which steam is admitted, a gumming or gluing roll running in said fount, a revolute supporting-roll, a segmental cylinder revolutely mounted in such position that, as it rotates, the perimeter thereof will come into contact with the perimeters of said gumming or gluing roll and said supporting-roll, means to rotate said gumming or gluing roll, said supporting-roll and said segmental cylinder, a scraping-knife reciprocally supported adjacent to said segmental cylinder, springs applied to said scraping-knife and adapted to maintain the same, normally, advanced, cams on the shaft of said segmental cylinder which are adapted to move or elevate said scraping-knife so as to allow said segmental cylinder to pass it and to release said scraping-knife just before said segmental cylinder passes from beneath it and a driven drying-cylinder, substantially as described.

In testimony that I claim the foregoing as my invention I have hereunto set my hand this 8th day of April, 1897.

HENRY A. FRAMBACH.
